CLAIM

The ornamental design for a benchtop fluid ejection device, as shown and described.

DESCRIPTION

FIG. 1 is a front, top, and first side perspective view of the benchtop fluid ejection device with a plate in a first position, an arm in a first position, and a latch in a first position;

FIG. 2 is a front view thereof;

FIG. 3 is a first side view thereof;

FIG. 4 is a second side view thereof;

FIG. 5 is a back view thereof;

FIG. 6 is a top view thereof;

FIG. 7 is a bottom view thereof;

FIG. 8 is a front, top, and second side perspective view thereof;

FIG. 9 is a back, top, and first side perspective view thereof;

FIG. 10 is a back, top, and second side perspective view thereof;

FIG. 11 is a front, top, and first side perspective view thereof with the plate in a second position;

FIG. 12 is another front, top, and second side perspective view thereof;

FIG. 13 is a front, top, and first side perspective view thereof with the arm in a second position;

FIG. 14 is another front, top, and second side perspective view thereof;

FIG. 15 is a front, top, and first side perspective view thereof with the latch in a second position; and,

FIG. 16 is another front, top, and second side perspective view thereof.

The broken lines illustrate portions of the benchtop fluid ejection device that form no part of the claimed design. The broken lines form no part of the claimed design.
